CLAIM

The ornamental design for seating furniture, as shown and described.

DESCRIPTION

FIG. 1 is an isometric view of seating furniture, in the form of a chair, incorporating our new design, wherein the break lines indicate indeterminate length;

FIG. 2 is a front isometric view thereof, wherein the break lines indicate indeterminate length;

FIG. 3 is a rear isometric view thereof; wherein the break lines indicate indeterminate length;

FIG. 4 is a side, partially isometric view thereof;

FIG. 5 is a front, partially isometric view thereof; wherein the break lines indicate indeterminate length;

FIG. 6 is a side elevation view thereof;

FIG. 7 is a front elevation view thereof, wherein the break lines indicate indeterminate length;

FIG. 8 is a top plan view thereof, wherein the break lines indicate indeterminate length; and,

FIG. 9 is a rear elevation view thereof, wherein the break lines indicate indeterminate length.
